COMBINED SIGNAL AND SPEED-CONTROLLING MECHANISM FOR RAILWAY-TRAINS.

No. 903,415.

Specification of Letters Patent. Patented Nov. 10, 1908.

Application filed August 3, 1907. Serial No. 386,938.

To all whom it may concern:

Be it known that we, JENS G. SCHREUDER, of Edgewood Park, Allegheny county, Pennsylvania, and VIBE K. SPICER, of Chicago, Cook county, Illinois, have invented a new and useful Combined Signal and Speed-Controlling Mechanism for Railway-Trains, of which the following is a full, clear, and exact description, reference being had to the accompanying drawings, forming part of this specification, in which:

Figures 1, 2 and 3 are diagrams illustrating our invention, the three views showing three different conditions of the movable parts and circuits under different track conditions; Figs. 4 and 5 are detail views illustrating the different positions of the combined home and distant track stop or trip.

In our application Serial No. 386,932, filed August 3, 1907, we have described and claimed trip actuated mechanism for the purpose of automatically controlling the speed of trains. In such mechanism we employ depending trip arms carried by the engine or train and adapted under certain conditions to engage and be actuated by trip or stop arms located along the track. Each engine or train is provided with two or more of the trip arms situated in different vertical planes, the operation of one of said arms effecting an emergency application of the brakes and the operation of the other arms effecting a service, or partial, application of the brakes.

Our present invention has relation more particularly to means whereby the passage of trains into and out of the track sections or blocks will automatically move the track trips or stops into and out of engaging positions, the object being to provide means whereby the mechanism on the train will be automatically operated to effect an emergency application of the brakes when the train comes to a home signal set at stop position, and to automatically effect a service application of the brakes when the train comes to a distant signal set at caution position, provided the speed of the train at that time exceeds the predetermined limit. We also provide home and distant signal mechanism in connection with the track trips or stops and controlled by the operation thereof, the circuits of the controlling magnets for

the signal blades being controlled by the movements of the track stops. In our pending application, Serial No. 386,937, filed of even date herewith, we have described and claimed mechanism of this character in which two sets of track trips or stops are employed, one set in connection with the home signal blades, and the other set in connection with the distant signal blades. Our present invention is designed to permit the use of a single set of track trips or stops, each of which has one controller arranged to move it towards and away from the track rails into position to be engaged by either one of the two trip arms on the engine or train, and a second controller arranged to move it in a vertical plane into and out of operative position, together with means for governing the operation of the controllers.

Our invention will be best understood by reference to the accompanying diagrams, which will now be described, premising, however, that various changes may be made by those skilled in the art without departing from the spirit and scope of our invention.

In these diagrams, the letters A, B, C designate three insulated sections or blocks of the track.

T, T', T² designate the track batteries which supply the respective blocks or sections with current.

D designates a distant signal blade placed in the usual manner at the entrance to the block A. D' is a similar blade at the entrance to the block B.

H is a home signal blade at the entrance to the block B, and H' is a similar blade at the entrance to the block C. For the purpose of simplifying the drawings, the home signal for the block A and the distant signal for the block C are not shown.

As will be understood by those skilled in the art, the arrangement shown constitutes a complete set of signals, and the application of the invention will be readily understood therefrom.

DM designates the magnet of the controller for actuating the signal blade D; DM' the magnet of the controller for actuating the signal blade D'; HM the magnet of the controller for actuating the signal blade H, and HM' the magnet of the controller which actuates the signal blade H'.

DS is a track trip or stop, which is placed in advance of the distant signal D, and which is arranged to be moved into and out of engaging position by an actuator or controller DC.

HDS is a combined distant and home stop arm, which is placed in advance of the home and distant signals H and D'. This trip or stop HDS is arranged to be moved towards and away from the adjacent track rail in the manner indicated in Fig. 4, so as to engage with either one of the trip arms P P' on the engine or train by means of a controller HC. It is also arranged to be moved into and out of operative position by being rocked in a vertical plane in either of its positions shown in Fig. 4, in the manner indicated in Fig. 5, by means of the controller DC'.

HS is a track trip or stop placed in advance of the home signal H' arranged to be moved into and out of operative position by the controller HC'.

R, R' and R² are relays which are connected across the respective blocks or sections, and are arranged to be short-circuited by the entrance of an engine or train, (indicated diagrammatically at X in Figs. 2 and 3) into the respective blocks. The armature *r* of the relay R controls in part the connection of the magnet of the controller DC with the battery B'. The armature *r'* of the relay R' controls the connections of the magnet of the controller DC' with the battery B'. The armature *r²* of the relay R² controls the connection of the magnet of the controller HC' with the battery B².

abc is a switch or circuit breaker, which is actuated by the movement of the track stop DS to control the circuit of the magnet DM, said magnet being connected in series and receiving its current supply from the battery B' through the armature *r* of a relay R, and through the switches *tuv* and *a'b'c'*. The switch *def* is connected to the track stop HDS, to be actuated thereby, as is also the switch *a'b'c'*. *lmn*, *tuv* and *xyz* are three switches which are connected to be operated in unison by the movement of the home signal arm H. The switch *lmn* controls the circuit of the magnet DM'; the switch *tuv* controls in part the circuit of the magnets DC and DM, being in series with the switch *abc*; and the switch *xyz* controls in part the circuit of the relay magnet R², this circuit being further controlled by a switch *l'm'n'*, operated by connection with the signal arm H'.

d'e'f' is a switch actuated by the track stop HS and controlling in part the circuit of the magnet HM'.

As shown, the parts are arranged to operate on what is known as the normally clear system. That is to say, when the track sections are clear and the parts are in working order, all of the track stops and all of the

signal blades will be in clear position, the circuits of the various controllers being closed. The presence of a train in any block, or the failure of any of the parts to work, opens the circuits of the corresponding signals and stops and immediately puts such signals and stops to stop position. It being remembered, therefore, that the parts are moved from clear to stop position by the breaking of the circuits of the respective controllers, the operation will be easily understood.

Fig. 1 shows the normal position with the blocks A, B, C clear and the parts in working order. When a train enters the block A at its left hand end, the relay R is at once short-circuited. This causes the armature *r* to fall, thereby opening the circuit of the controller magnet DC and moving the stop arms DS up into operative position. This movement of the stop arm breaks the circuit of the magnet DM at the point *b* and the signal arm D goes to caution position. The signal arm H does not at this time go to stop position, owing to the fact that the circuit of the magnet HM remains closed through the switch *a'b'c'*, and through the armature *r'* of the relay R'. As soon as the train passes out of the block A the relay R again picks up but the closing of the circuit of the controller DC to move the stop arm DS to clear position is not effected until the train passes into the block C, as hereinafter described.

When the train enters the block B, the relay R' is short-circuited. This causes the armature *r'* to drop and opens the circuit of the controller HC and of the magnet HM. The home signal arm H goes to stop, thereby opening the three switches *lmn*, *tuv* and *xyz*. The opening of the circuit of the magnet HC moves the stop arm HDS into position to be engaged by the trip arm P to effect an emergency application of the brakes as soon as the controller DC' has moved said trip into upright position. The opening of the switch *lmn* opens the circuit of the magnet DM', and the distant signal D' goes to caution position. The circuit of the magnet R² is also opened, thereby dropping the armature *r²* and opening the circuit of the controller DC', which brings the track trip or stop HDS to operative position. The movements of the track stop HDS also opens the switches *def* and *a'b'c'*, as shown in Fig. 2.

As the train leaves the block B and enters the block C, the relay R' at once picks up. This closes the circuit of the controller HC, and the track stop HDS is moved thereby laterally in position to engage the trip arm P' on the locomotive. It also closes the circuit of the magnet HM and the home signal arm H goes to clear position, thereby closing the three switches *lmn*, *tuv*, and *xyz*.

This closes the circuit of the magnets DM, and the stop DS, and the distant signal arm D go to clear position. The distant signal arm D', however, and the track stop HDS remain in said position so long as the train is in the block C. The entrance of the train into the block C of course short-circuits the relay R* and opens the circuit of the controller HC', thereby setting the track stop HS to operative position. This opens the switch d'e'f' and thereby the circuit of the magnet HM', and the home signal arm H' goes to danger position, opening the switch l'm'n'. So long as the switch l'm'n' remains open, the circuit of the controller DC' cannot be closed, and the circuit of the magnet DM' remains open at the switch def. When the train entirely clears the block C, the relay R* again picks up, which moves 20 the track stop HS to clear position, and closes the circuit of the magnet HM'. This causes the home signal arm H' to go to clear position, which closes the switch l'm'n' and thereby the circuit of the magnet R*. This 25 in turn closes the circuit of the controller DC', moves the stop HDS out of operative position, and closes the circuit of the magnet DM'. The distant signal arm D' now clears. While for reasons before explained, the 30 home signal for the block A and the distant signal for the block C are not shown, it will be readily understood that in a complete installation, the track stops DS and HS will each have two controllers similar to those of 35 the track stop HDS, actuated and controlled in the same manner.

The several controllers for actuating the track stops, and the signal blades, may be of the well-known electro-pneumatic type, 40 or of any other suitable variety. It is also obvious that various changes may be made in the circuit connections without affecting our invention.

The advantages of our invention result 45 from the provision of the track stops operated by the passage of trains into and out of their respective blocks, together with the home and distant signal mechanism having its actuators controlled by the movement of 50 the track stops, the latter forming a simple and positive means for the automatic control of trains, whereby it is rendered impossible for an engineer to proceed past the home signal set at stop, or to proceed past 55 a distant signal set at caution, above the predetermined speed.

While, as above stated, we have shown our invention as applied to a system in which the signal and stops are all in a clear position when the corresponding blocks are clear and the parts are in working order, it is obvious that it is equally applicable to a system of the reverse character wherein the stops and signals are normally at danger 65 and are cleared by train movements.

What we claim is:

1. In train controlling apparatus, a stop or trip, an actuator for moving the same from one operative position to another, a second controller for moving the stop into and out of its operative positions, and means controlled by the passage of trains into and out of the blocks for controlling the operations of the actuators; substantially as described. 75

2. In train controlling apparatus, a stop or trip having two operative positions, an actuator for moving the same from one operative position to the other, a second controller for moving the stop out of its operative positions, means controlled by the passage of trains into and out of the blocks for controlling the operation of the actuators, and signal mechanism controlled by the movements of the stops or trips; substantially as described. 80

3. In train controlling apparatus, home and distant signals, a track stop or trip having two operative positions, an actuator for moving the same from one position to the other, a second actuator for moving the same into and out of its operative positions, relays operated by the passage of trains into and out of the track blocks for controlling the actuators, actuators for the home and distant signal blades, and connections controlled by the movements of the stops or trips for controlling the last named actuators; substantially as described. 90

4. In a block signal system, means for automatic train control, consisting of a track trip or stop having two operative positions, an actuator for moving the trip or stop from one position to the other, a second actuator for moving the stop or trip into and out of its operative positions, home and distant signal mechanism, actuators therefor controlled by the movement of the track stop or trip, and means whereby each track stop or trip is held in one operative position so long as 110 the adjacent block is occupied, and is held in the other operative position so long as the next succeeding block is occupied; substantially as described. 105

5. In train controlling apparatus, a track stop or trip having two operative positions, and also movable into and out of operating position, actuating means for shifting the same from one position to another, other actuating means for moving the trip into and 115 out of operating position, means controlled by the passage of trains for controlling both actuating means, together with a signal, and actuating means therefor controlled by the movements of the track trips; substantially 120 as described.

6. In train-controlling apparatus, a track stop or trip having two positions at different lateral distances from the longitudinal center of the track, and in each of which 125 130

positions it is arranged to exert a positive operation on a passing train, and means controlled by the passage of a train for shifting said stop laterally from one position to the other; substantially as described.

7. In train controlling apparatus, a track stop or trip, having two different positions at different lateral distances from the longitudinal center of the track in which it exerts a positive operation on a passing train, home and distant signals and actuating mechanisms therefor, actuating mechanisms for the track stops or trips, and related electric circuits between the actuating mechanism for the track stops and the actuated mechanisms for the signals whereby the actuation of one effects a corresponding proper action of the other; substantially as described.

8. In train controlling apparatus home and distant signals and operating circuits therefor, track trips each having a position corresponding to the different positions of each of a pair of home and distant signals, and shifting mechanism for the trips having their circuits inter-related with the circuits of the home and distant signals; substantially as described.

9. In train controlling apparatus home and distant signals and operating circuits therefor, controlled by the passage of trains, track trips each having a position corresponding to the different positions of each of a pair of home and distant signals, and shifting mechanism for the trips having their circuits inter-related with the circuits of the home and distant signals, and also controlled by the passage of trains; substantially as described.

10. In train-controlling apparatus, a stop signal, a caution signal, and a track trip, said trip having two operative positions corresponding respectively to the stop and safety positions of the signals, and actuating devices for shifting the trip and signals interrelated with each other to effect correlated operations of the signals and stop; substantially as described.

11. In train controlling apparatus, a shiftable track trip having movements in two different planes, actuating devices for shift-

ing said trip, track signals, actuating devices therefor, and means controlled in part by the passage of trains and in part by the movement of the signals for controlling the actuating devices for said trips; substantially as described.

12. In train controlling apparatus, a shiftable track trip having movements in two different planes, actuating devices for shifting said trip, track signals, actuating devices therefor, and means controlled in part by the passage of trains and in part by the movements of the signals for controlling the actuating devices for said trips, and means controlled in part by the passage of trains and in part by the movements of the track trips, for controlling the actuating devices for the signals; substantially as described.

13. In train controlling apparatus, a shiftable track trip having movements in two different planes, actuating devices for shifting said trip, track signals, actuating devices therefor, and electrical circuits controlled in part by the passage of trains and in part by the movement of the signals for controlling the actuating devices for said trips; substantially as described.

14. In train controlling apparatus, a shiftable track trip having movements in two different planes, actuating devices for shifting said trip, track signals, actuating devices therefor, electrical circuits controlled in part by the passage of trains and in part by the movement of the signals for controlling the actuating devices for said trips, and electrical circuits controlled in part by the passage of trains and in part by the movements of the track trips, for controlling the actuating devices for the signals; substantially as described.

In testimony whereof, we have hereunto set our hands.
